INVENTOR

T. A. O'REILLY,

BY
A. B. Gleeson & Co
ATTORNEYS

UNITED STATES PATENT OFFICE.

THOMAS A. O'REILLY, OF ST. LOUIS, MISSOURI.

BOTTLE-HOLDER.

1,340,974.

Specification of Letters Patent. Patented May 25, 1920.

Application filed May 5, 1919. Serial No. 294,734.

To all whom it may concern:

Be it known that I, THOMAS A. O'REILLY, a citizen of the United States, residing in the city of St. Louis and State of Missouri, have invented certain new and useful Improvements in Bottle-Holders; and I do declare the following to be a full, clear, and exact description of the invention, such as will enable others skilled in the art to which it appertains to make and use the same.

This invention relates to improvements in bottle holders and more particularly to devices for supporting nursing bottles.

The object of my invention is to provide a bottle holder of extremely simple and improved construction.

With this and other objects in view, the invention consists in certain novel features of construction and arrangement of parts as will be described in the specification and claim and clearly illustrated in the accompanying drawings which form a part of this application and in which:

Figure 1 is a side elevation of my bottle holder.

Fig. 2 is a front end elevation thereof.

Fig. 3 is a rear end view of the device.

Fig. 4 is a top plan view.

Fig. 5 is a perspective view of the invention, and

Fig. 6 is a vertical section on the line 6—6 of Fig. 2.

As illustrated in the accompanying drawing, my invention includes a substantially H-shaped base section consisting of a pair of T couplings *o* and *p* connected by a tube or rod *h* formed of metal, wood or the like, the ends being externally threaded for engagement with the internal threads of the 35 couplings. Disposed at right angles to the rod *h* are horizontally extending legs *m*, *n*, *r* and *v* whose inner ends are threaded for engagement with the couplings *o* and *p*, the free ends of said legs being covered by 40 balls *l* formed of rubber or other suitable material and for the purpose of protecting furniture, etc., from being marred.

Rising vertically from the base at the angles of intersection of the rod *h* and legs 50 *m*, *n*, *r* and *v* is a pair of standards each of which is adjustable. Each of these standards includes a short hollow metal section *e*, *f*, which is internally threaded to engage the externally threaded end of an extension 55 *c*, *d*, the purpose of the threaded engagement being to allow vertical adjustment of said extension.

The free end of each extension *c*, *d*, is provided with a longitudinally extending threaded socket *g* adapted for the reception 60 of a screw *w*, as clearly illustrated in Fig. 6 of the drawings. The screws *w* are loosely received in the yokes or supporting members *a* and *b* at points midway their lengths and extend vertically downward into the afore- 65 said threaded sockets *g*, the yokes being rotatable on the screws permitting the extensions *c* or *d* to vertically adjust the standards without turning said yokes or supporting members.

The front supporting member *a* is formed with more of a continuous curve than the rear member so as to conform with the shape of the neck of the ordinary nursing 70 bottle.

When using this holder, the rear yoke, or supporting member, is adjusted considerably higher than the front one, so that the contents will flow to the mouth of the bottle, which is supported on the front yoke. The 80 bottleholder may be used on a bed, the legs on the base being of such length as to provide a substantial support and prevent tipping over the device.

The legs may be covered over with the 85 bed clothes and pillows, thereby further insuring against tipping the holder over.

From the foregoing description, taken in connection with the accompanying drawings, the construction and operation of the 90 invention will be readily understood without requiring a more extended explanation.

Various changes in the form, proportion and the minor details of construction may be resorted to without departing from the 95 principle or sacrificing any of the advantages of the claimed invention.

I claim:

A device of the character described, comprising a substantially H-shaped base, sections rising from the base at the angles of intersection, extensions having screw threaded portions to engage said sections to adjustably support them on said sections, 100 said extensions having longitudinally extending threaded sockets in their upper ends supporting yokes having stems thereon adapted to be received in said sockets to form swivel connections between the extensions and yokes.

In testimony whereof I have hereunto set my hand.

THOMAS A. O'REILLY.
